UNITED STATES PATENT OFFICE.

DWIGHT R. CURTENIUS, OF KALAMAZOO, MICHIGAN, ASSIGNOR TO KALAMAZOO STOVE COMPANY, OF KALAMAZOO, MICHIGAN.

DESIGN FOR A KITCHEN-CABINET.

46,047.

Specification for Design.

Patented July 7, 1914.

Application filed May 2, 1914. Serial No. 836,035. Term of patent 14 years.

To all whom it may concern:

Be it known that I, DWIGHT R. CURTENIUS, a citizen of the United States, residing at 420 West Cedar street, in the city and county of Kalamazoo, State of Michigan, have invented a new, original, and ornamental Design for Kitchen-Cabinets, of which the following is a specification, reference being had to the accompanying drawing, forming a part thereof.

The figure is a perspective view of a kitchen cabinet showing my new design.

I claim:

The ornamental design for a kitchen cabinet, as shown.

DWIGHT R. CURTENIUS.

Witnesses:

MORGAN E. PERSING,
WOODBURY RANSOM.
